UNITED STATES PATENT OFFICE.

GEORGE L. ROCKWELL, OF MINNEAPOLIS, MINNESOTA.

DESIGN FOR A BADGE.

SPECIFICATION forming part of Design No. 34,888, dated August 6, 1901.

Application filed May 18, 1901. Serial No. 60,944. Term of patent 14 years.

To all whom it may concern:

Be it known that I, GEORGE L. ROCKWELL, a citizen of the United States, residing at Minneapolis, Minnesota, (and whose post-office address is General Delivery, Minneapolis, Minnesota,) have invented and produced a new and original Design for a Badge, of which the following is a specification, reference being had to the accompanying drawing, forming a part thereof.

A single view of the drawing shows the badge in plan or face view.

As shown in the drawing, the material or leading features of my design are a pyramid *a*, circumscribed by a circle *b*; the representation of a man seated in an easy-chair *c* reading a newspaper or magazine; the representation of a workman with sleeves rolled up carrying a sledge-hammer or maul in one hand; the representation of a night sky, including stars *e* and moon *f*; the representation of an ocean *g*, on which floats an ocean-steamer *h* and sailing-yacht *m*, and the representation of a factory *k*. The pyramid is shown as built from large blocks of masonry, and the said pyramid has the effect of dividing the circle *b* into approximately three equal parts.

In the above design the several characteristic features have significant meanings. For instance, the pyramid *a* is indicative of strength, and the circle *b*, which is indicative

of the twenty-four hours of the day or complete rotation of the earth, is divided into approximately three equal parts, indicative of the natural division of the day into three equal parts—to wit, eight hours for work, eight hours for recreation, and eight hours for sleep.

The workman, the ocean-steamer, and the factory at the left of the pyramid are all indicative of work, the man seated in the easy-chair *c* reading, as well as the pleasure-yacht *m*, both indicated at the right of the pyramid, are indicative of recreation or self-improvement, while the night sky beneath the pyramid is indicative of rest or sleep.

The design above described is especially intended for application as a badge or insignia for labor organizations, and particularly for those advocating the eight-hour labor day, and is adapted to be applied to medals, buttons, lockets, banners, and various other articles.

Having described my invention, what I claim as new, and desire to secure by Letters Patent of the United States, is—

The design for a badge, substantially as herein shown and described.

In testimony whereof I affix my signature in presence of two witnesses.

GEORGE L. ROCKWELL.
